UNITED STATES PATENT OFFICE.

ROBERT S. GOULD, OF EAST ORANGE, NEW JERSEY.

CURTAIN-POLE BRACKET.

SPECIFICATION forming part of Letters Patent No. 319,089, dated June 2, 1885.

Application filed March 28, 1885. (No model.)

To all whom it may concern:

Be it known that I, ROBERT S. GOULD, of East Orange, in the county of Essex and State of New Jersey, have invented certain new and useful Improvements in Curtain - Pole Brackets, of which the following is a specification.

This invention has reference to an improved extensible curtain-pole bracket; and it consists 10 of a bracket provided with a fixed nut, and of a pole-supporting piece having a threaded shank passing through the guide, the shank being flattened at one side, so as to be clamped by a set-screw passing through the nut, as 15 will more fully appear hereinafter, and finally be pointed out in the claims.

In the accompanying drawings, Figure 1 represents a side elevation of my improved curtain-pole bracket, shown partly in section; 20 and Fig. 2 is a top view of the same.

Similar letters of reference indicate corresponding parts.

A in the drawings represents a bracket, which is made of two pieces that are attached 25 to the wall, and which are riveted or otherwise attached to a fixed nut, B, at their outer ends. Through the nut B passes the threaded shank C of a curtain-pole-supporting piece, D, the bent outer part, D, of which has a set-screw, 30 E, for retaining the pole in position thereon. The threaded shank C is made flat at one side by partly cutting away the threads, so as to be clamped by a set-screw, B', passing through

the nut B. By cutting away the threads at one side of the shank C the turning of the shank C in the nut B is prevented after the supporting-piece D has been adjusted to support the curtain-pole at a proper distance from the wall. The nut B is made of suitable length to give a steady and reliable support for the shank C, which is turned therein by taking hold of the bent supporting-piece D until the required distance from the wall is obtained, after which the bent portion is secured rigidly in position by the clamping-screw B' and prevented from turning.

Having thus described my invention, I claim as new and desire to secure by Letters Patent—

1. The combination of a supporting-bracket having a fixed screw-nut with a bent curtain-pole-supporting piece having a threaded shank passing through said nut, substantially as set forth.

2. The combination of a supporting-bracket having a fixed screw-nut and a clamp-screw with a bent curtain-pole-supporting piece having a threaded shank flattened or cut away at one side, substantially as set forth.

In testimony that I claim the foregoing as my invention I have signed my name in presence of two subscribing witnesses.

ROBT. S. GOULD.
